UNITED STATES PATENT OFFICE

2,574,343

WATCH MOVEMENT CENTER SECOND
HAND DRIVEFriedrich Meyer, Grenchen, Switzerland, assignor
to Felsa A.-G., Grenchen, Switzerland, a joint-
stock companyApplication August 6, 1947, Serial No. 766,559
In Switzerland April 26, 1944Section 1, Public Law 690, August 8, 1946
Patent expires April 26, 1964

8 Claims. (Cl. 58—59)

1

Watch movements with a central hand often possess for this hand a spindle, the drive wheel of which is geared in the normal sequence of the wheel-work. This is the reason why the backlash between the teeth of the wheels is ineffective and why the very long second hand follows the jumping motion of the escapement. This arrangement always requires a specially designed rough movement which is not suitable for watches with the hand fixed on the spindle of the fourth wheel. If, however, the wheels of the watch movement are arranged with a central hand for the seconds according to the invention, i. e. if the pinion of the second hand is arranged as a third member between the intermediate wheel and the fourth wheel, it is possible to also utilize the blank of this watch movement for a watch with an eccentrically-arranged second hand.

Preferably the drive of the second hand, rotating in the centre of the watch, is effected by the third wheel and the drive of the fourth wheel by means of an additional wheel which receives the movement from the second drive and which is arranged rotatably on the spindle of the third wheel.

The drawing represents, by way of example, two executional forms of the watch movement according to the invention.

Fig. 1 is a partial plan and

Fig. 2 a section on the line A—B—C—D—E of Fig. 1 of the first executional form.

Fig. 3 is a schematic plan and

Fig. 4 a section on the line I—II—III—IV of Fig. 3, both figures referring to the second executional form.

With reference to Figs. 1 and 2, the plate is marked 1. 2 is the bridge in which the wheels inserted between the driving means and the escapement are rotating. These are the escape fourth wheel 5, the wheel 6, the third wheel 7 and the center-wheel 8, the drive of which being in mesh with the gear rim of the spring barrel 10.

Between the third wheel 7 and the fourth wheel for the seconds 6 is inserted the pinion 11 of spindle 14, which penetrates through the hollow shaft 15 for the minutes and which carries the hand for the seconds 13 in the center. The transmission of the motion of the pinion 11 received from the third wheel 7 is effected through engagement with the additional wheel 12 meshing with the pinion of the fourth wheel 6 and arranged rotatably on the spindle of the third wheel 7.

2

It may be seen from the drawing that the wheels 7 and 12 possess the same diameter and that this is always the case for wheels arranged according to the invention. Should the pinion 11 and the corresponding spindle be omitted, and should the wheel 12 be fixed on its spindle, the usual wheel arrangement is obtained, where the eccentric hand for the seconds may be fixed on the spindle of the fourth wheel.

10 Naturally, the one hand for the seconds does not exclude the other; both hands may be used simultaneously.

In the executional form according to Figs. 3 and 4, the various wheels of the watch movement are again arranged between the plate 1 and the bridge 2. They are: the fourth wheel 6, the third wheel 7, the center-wheel 8 with its pinion 9 and the spring barrel 10. The pinion 11 is fixed on the spindle 14 which penetrates through the hollow spindle 15 for the minutes and which carries centrally the hand for the seconds 13.

The third wheel 7 is fixed on its spindle 16. The latter possesses below the wheel 7 a collar 17, which serves as a rest for a flanged tubular piece 18. On the flange 19 rests an additional transmission wheel 20 which has exactly the same size as the third wheel 7 and which also engages with the pinion 11, transmitting its motion on to the pinion of the fourth wheel 6. Thus, the pinion, the spindle carrying centrally the hand for the seconds and the transmission wheel are arranged in series with the remaining wheels of the watch movement, enabling this hand to carry out the jumping motion of the fourth wheel without being influenced by the backlash of the teeth.

40 The transmission wheel 20, resting on the flange 19, is separated from the third wheel 7 by means of a guiding disc 21 which is also arranged rotatably on the flanged tubular piece 18 and which, provided with an opening, has the appearance of a toothless wheel, its thickness being such that it prevents the tilting of the transmission wheel 20 resting on the flange 19.

45 What I claim is:

50 1. In a timepiece movement, a center seconds hand spindle, an arbor, a third wheel and pinion fixed to said arbor, a pinion fixed to said center seconds hand spindle and in mesh with said third wheel, a fourth wheel spindle, a fourth wheel fixed to said fourth wheel spindle, an intermediate drive means in engagement with the 55 pinion of said center seconds hand spindle and

in drive connection with said fourth wheel spindle.

2. In a timepiece movement, a center seconds hand spindle, a hollow shaft traversed by said center seconds hand spindle, a center wheel fixed to said hollow shaft, an arbor, a third wheel and pinion fixed to said arbor and engaged by said center wheel, a pinion fixed to said center seconds hand spindle and in mesh with said third wheel, a fourth wheel spindle, a fourth wheel fixed to said fourth wheel spindle, and intermediate drive means in engagement with the pinion of said center seconds hand spindle and in drive connection with said fourth wheel spindle.

3. In a timepiece movement, a center seconds hand spindle, an arbor, a third wheel and pinion fixed to said arbor, a pinion fixed to said center seconds hand spindle, and in mesh with said third wheel, a fourth wheel spindle, a fourth wheel and a pinion both fixed to said fourth wheel spindle, and an intermediate wheel loosely mounted on said arbor and meshing with the pinions of said center seconds hand spindle and of said fourth wheel spindle.

4. In a timepiece movement, a center seconds hand spindle, a hollow shaft traversed by said center seconds hand spindle, a center wheel fixed to said hollow shaft, an arbor, a third wheel and pinion fixed to said arbor and engaged by said center wheel, a pinion fixed to said center seconds hand spindle and in mesh with said third wheel, a fourth wheel spindle, a fourth wheel and a pinion both fixed to said fourth wheel spindle, and an intermediate wheel loosely mounted on said arbor and meshing with the pinions of said center seconds hand spindle and of said fourth wheel spindle.

5. In a timepiece movement, a center seconds hand spindle, an arbor, a third wheel and pinion fixed to said arbor, a pinion fixed to said center seconds hand spindle, and in mesh with said third wheel, a fourth wheel spindle, a fourth wheel and a pinion both fixed to said fourth wheel spindle, a tubular piece having a flange, supported on said arbor, a rotatable intermediate wheel resting on said flange of said tubular piece and meshing with the pinions of said center seconds hand spindle and of said fourth wheel spindle, and a guide disk arranged between said third wheel and said rotatable intermediate wheel to prevent tilting of the latter.

6. In a timepiece movement, a center seconds hand spindle, a hollow shaft traversed by said center seconds hand spindle, a center wheel fixed to said hollow shaft, an arbor, a third wheel and pinion fixed to said arbor and engaged by said center wheel, a pinion fixed to said center seconds

hand spindle, and in mesh with said third wheel, a fourth wheel spindle, a fourth wheel and a pinion both fixed to said fourth wheel spindle, a tubular piece having a flange, supported on said arbor, a rotatable intermediate wheel resting on said flange of said tubular piece and meshing with the pinions of said center seconds hand spindle and of said fourth wheel spindle, and a guide disk arranged between said third wheel and said rotatable intermediate wheel to prevent tilting of the latter.

7. In a timepiece movement, a center seconds hand spindle, an arbor, a third wheel and pinion fixed to said arbor, a pinion fixed to said center seconds hand spindle, and in mesh with said third wheel, a fourth wheel spindle, a fourth wheel and a pinion both fixed to said fourth wheel spindle, a tubular piece having a flange mounted on said arbor, a rotatable intermediate wheel resting with its one face on said flange of said tubular piece and meshing with the pinions of said center seconds hand spindle and of said fourth wheel spindle, and a guide disk arranged between said third wheel and said rotatable intermediate wheel and in contact with the other face of the latter.

8. In a timepiece movement, a center seconds hand spindle, a hollow shaft traversed by said center seconds hand spindle, a center wheel fixed to said hollow shaft, an arbor, a third wheel and pinion fixed to said arbor and engaged by said center wheel, a pinion fixed to said center seconds hand spindle, and in mesh with said third wheel, a fourth wheel spindle, a fourth wheel and a pinion both fixed to said fourth wheel spindle, a tubular piece having a flange mounted on said arbor, a rotatable intermediate wheel resting with its one face on said flange of said tubular piece and meshing with the pinions of said center seconds hand spindle and of said fourth wheel spindle, and a guide disk arranged between said third wheel and said rotatable intermediate wheel and in contact with the other face of the latter.
